CLAIM

I claim the ornamental design for the blender coupler for a canning jar, as shown and described.

DESCRIPTION

FIG. 1 is a top perspective view of a first embodiment of a blender coupler for a canning jar showing my new design;

FIG. 2 is a bottom perspective view thereof;

FIG. 3 is a side elevation thereof;

FIG. 4 is a side elevation thereof opposite that shown in (FIG. 3);

FIG. 5 is an end view thereof;

FIG. 6 is an end view thereof opposite that shown in (FIG. 5);

FIG. 7 is a top perspective view of a second embodiment thereof;

FIG. 8 is a bottom perspective view thereof;

FIG. 9 is a side elevation thereof;

FIG. 10 is a side elevation thereof opposite that shown in (FIG. 9);

FIG. 11 is an end view thereof;

FIG. 12 is an end view thereof opposite that shown in (FIG. 11);

FIG. 13 is a top perspective view of a third embodiment thereof;

FIG. 14 is a bottom perspective view thereof;

FIG. 15 is a side elevation thereof;

FIG. 16 is a side elevation thereof opposite that shown in (FIG. 15);

FIG. 17 is an end view thereof; and,

FIG. 18 is an end view thereof opposite that shown in (FIG. 17).

Contour lines indicate only shading or reflectivity and do not indicate surface ornamentation.
